[57] CLAIM

The ornamental design for a combined drink stirrer and container for a liquid refrigerant, as shown and described.

DESCRIPTION

FIG. 1 is a top plan view of a combined drink stirrer and container for a liquid refrigerant showing my new design;

FIG. 2 is an elevational view, the opposite side being substantially the same in appearance;

FIG. 3 is a view partly in section looking from the right of FIG. 2, the opposite side being substantially the same in appearance; and

FIG. 4 is a bottom plan view.
